FOLDING MACHINE

Lionel G. Vachon, Groveland, Mass., assignor to
 Boston Machine Works Company, Lynn, Mass.,
 a corporation of Massachusetts

Application June 15, 1944, Serial No. 540,518

8 Claims. (Cl. 69—8)

This invention relates to machines for doubling back the margins of a preshaped piece of flexible sheet material to form a finished edge or edges thereon. The doubled-back portion, or the area against which it is to be laid, is preferably first cemented so that when it is pressed against the face of the piece after being doubled back, it will be held fast. For example, certain shoe parts may be made in this manner, for ornamental purposes or otherwise, by doubling back the margin of a piece of soft split leather or equivalent flexible sheet material which has been previously cut to shape. A thin stiffening element of suitable material such as stiff paper may be cemented to the blank before the margins are doubled back. The margins will in such case be bent back about the edges of the stiffening element and will be cemented to the exposed face thereof.

It is an object of the invention to provide a mechanism of simple but effective structure adapted to perform the doubling-back operation and to press the resulting hem firmly while the cement on the cemented areas takes an initial set. Various other advantageous features of structure will be apparent from the following description of certain embodiments of the invention illustrated in the accompanying drawings, of which

Figure 1 is a perspective view of a blank for a rectangular article, having a stiffening element 30 thereon.

Figure 2 is a perspective view of the finished article resulting from the blank shown in Figure 1.

Figure 3 is a perspective view of a finished article of a different contour.

Figure 4 is a perspective view of a finished article of circular shape.

Figure 5 is a perspective view of a folding machine embodying the invention.

Figure 6 is a plan view of the machine with the top plate removed, showing certain parts in section.

Figure 7 is a vertical sectional view of the machine on the line 7—7 of Figure 5.

Figures 8, 9 and 10 are fragmentary sectional views similar to Figure 7 but showing the working parts in different positions of operation.

Figure 11 is a fragmentary sectional view of a modified form of the invention.

Figure 12 is a fragmentary perspective view of a set of folder elements adapted to form the article shown in Figure 4.

The machine illustrated in Figure 5 comprises a base or support 20 which, for use, is preferably

secured to a bench or table (not shown). The base is provided with a shallow central recess 22 within which is loosely fitted a platen 24 the function of which is hereinafter explained. 5 Mounted on the base 20 is a frame 26 having a central aperture approximately registering with the recess 22. This aperture forms a cavity which is shaped to receive the work. The machine illustrated in Figure 5 is adapted to operate on blanks such as the one shown in Figure 1 from which the rectangular article shown in Figure 2 is made. Hence the recess 22, the platen 24 and the aperture in the frame 26 are all of similar rectangular shape.

10 The blank shown in Figure 1 may consist of a piece of thin split leather 30 having its grain or finished face down. A stiffener 32 is cemented to the reverse face of the leather piece, the stiffener being cut to the size and shape of the finished piece shown in Figure 2. The margins 34 of the blank 30 project beyond the edges of the stiffener 32 and are trimmed as at 36 so that they will not overlap when doubled back as in Figure 2.

15 Mounted on the frame 26 are guide members 40 which serve to guide a group of slides or folder members 42, 44, 46, 48 and also to support a cover plate 50 which is secured thereon. The cover plate 50 has a central aperture which has the same size and shape as the aperture in the frame 26 and is directly above the latter so that it adds to the depth of the work-receiving cavity. The guide members 40 and cover plate 50 form passages in which are slidably fitted the four folder members. The folder members present 20 toward the cavity respective edge portions 52, 54, 56 and 58 which are movable inwardly to project into the cavity from the sides thereof, as indicated in Figure 9. These edge portions are beveled at their respective ends to permit maximum penetration of all into the cavity. The folder members are preferably operated simultaneously by any suitable mechanism for the purpose. As shown, an actuator for the member 42 is provided in the form of a finger 60 which is 25 rockable about a shaft 62 to press against a pusher 64 which bears against the outer edge of the member 42 and is confined between guides 65, the guiding edges of which are parallel to the guideway of member 42. The folder members 44 and 46, which are adjacent to the member 42 at opposite sides of the path thereof, are moved inwardly toward each other in response to inward movement of the member 42. As indicated in 30 Figure 6, this is done by means of cam edges 70 and 72 on the member 42 which engage respec-

35 tively the outer edges of the members 44 and 46. The folder members 42, 44 and 46 are held in their respective positions by a lock mechanism which is not shown. The folder member 48 is 40 held in its position by a lock mechanism which is not shown. The folder members 42, 44 and 46 are held in their respective positions by a lock mechanism which is not shown. The folder member 48 is 45 held in its position by a lock mechanism which is not shown. The folder members 42, 44 and 46 are held in their respective positions by a lock mechanism which is not shown. The folder member 48 is 50 held in its position by a lock mechanism which is not shown. The folder members 42, 44 and 46 are held in their respective positions by a lock mechanism which is not shown. The folder member 48 is 55 held in its position by a lock mechanism which is not shown.

tively cam edges 74 and 76 on the adjacent members 44 and 46. These cam edges are all preferably inclined at angles of 45° to the directions of movement of the folder members, and the mode of operation thereof is evident from Figure 6. In like manner, inward movement of members 44 and 46 results in inward movement of the member 48. This is brought about by cam edges 78 and 80 on the members 44 and 46, respectively, which engage cam edges 82 and 84, respectively, on the member 48. Thus when the folder member 42 is pushed inward, it drives the other three members inward so that each of the four folder members then protrudes into the cavity as indicated in Figures 9 and 10. The inward movement of the member 48 is against the tension of a retracting spring 90, the ends of which are anchored to the member 48 and the frame 26 respectively. When the member 42 is released, therefore, the spring retracts the member 48 which in turn retracts the other three folder members through the interengagement of the cam edges hereinbefore described, as is evident from Figure 6.

For effective operation of the finger 60, it may be mounted on a hub 92 which turns on the shaft 62. An operating lever 94, provided with a handle 96, projects from the hub 92 and provides effective mechanical advantage. The ends of the shaft are secured in suitable blocks 98 at the rear of the base 20. As shown in Figure 5, the lever 94 is arranged so that it can be swung forward and down across the work-receiving cavity and can be swung upward and backward to impart inward movement of the folder members. The lever 94 carries a pusher plate 100 which has a shape similar to, and is slightly smaller than, the work-receiving cavity in the frame 26 and cover plate 50 and is arranged to enter the cavity when the lever is swung forward and down.

The operation of the device is as follows. When the operating lever 94 is in an intermediate position such as is shown in Figure 5 or Figure 7, the pusher 100 is clear of the cavity and the folder members are retracted so that the cavity is ready to receive a piece of work. A blank is placed on the cover plate over the cavity. In order to facilitate proper centering, any suitable gaging means can be employed. As shown in Figure 5, a gage plate 102 having a central aperture shaped to receive a blank 30 in flat condition is mounted on the cover plate 50. The edges around the aperture center the blank over the cavity as indicated in Figure 7. Just before the blank is put in position over the cavity, the margins 34 are preferably coated with fresh cement.

The lever 94 is then swung down so that the pusher plate 100 engages the blank and forces the body portion thereof and its stiffener 32 to the bottom of the cavity as in Figure 8. This causes the sides of the cavity to bend the margins 34 of the blank up out of the plane of the blank. The lever 94 is then swung upward to withdraw the pusher plate 100 from the cavity. In order to prevent the blank from following the pusher plate out of the cavity, overhanging shoulders may be provided to catch the edges of the margins 34. Such shoulders may be conveniently formed by suitable grooves 104 in the inner edges of the folder members, as indicated in Figures 8 and 9.

Further rearward movement of the operating lever 94 causes the finger 60 to actuate the folder members. The latter move into the cavity, as indicated in Figure 9, and fold the upstanding margins 34 back against the body of the blank. The

platen 24 is then elevated to press the work firmly against the projecting portions of the folder members, as indicated in Figure 10, while the cement takes an initial set. The platen is actuated by any suitable means such as a plunger 108 which engages it from below and is in turn actuated by a pedal operated lever (not shown) or any equivalent device.

When the lever 94 is swung back to its initial intermediate position, releasing the folder members, the latter are retracted by the spring 90. The platen 24 may then be further raised to eject the finished work from the cavity as indicated in dotted lines in Figure 10.

In some cases it may be desired to operate on a blank which is not provided with a stiffening member. For example the work may consist of blanks 120 cut from soft, flexible leather or the like, and nothing more. In order to prevent buckling of such blanks and to make sure that the doubling back will be on definitely predetermined lines of fold, the pusher 122 (Figure 11) is provided with a ridge 124 running around its contour and projecting toward the work. The ridge is made sharp enough to indent and crease the work as at 126 but not to cut or injure it when the lever 94 is swung down to push the work into the cavity. The inward movement of the folder members causes the margins 130 to fold back along the crease lines 126 and the platen 24 is then elevated to press the resulting hem flat and smooth.

The mechanism illustrated in Figure 5 can be used to operate on blanks having quadrilateral shapes other than rectangles. For example, the blanks may have side edges which are concave, as in Figure 3, or are convex or otherwise. In each case, the cavity and the associated parts of the mechanism are shaped correspondingly and the margins are beveled at the corners of the quadrilateral so that there is no overlapping of marginal portions when they are doubled back as at 132 and 134.

If circular work is desired, as in Figure 4, or work of other shapes having no definite corners, an annular margin 136 will necessarily wrinkle or gather when doubled back. To make a smooth job, it is necessary to present to such work a continuous folding edge. Hence the folder members may be made as indicated in Figure 12. Each of the folder members 140, 142, 144, 146 presents an arcuate folding edge the ends of which are cut away above, as at 150 or below as at 152, to provide overlapping portions which form a virtually continuous folding surface which contracts against the upstanding margin of the work when the folder members are moved inward into the cavity.

I claim:

1. In a device for doubling back the margins of a piece of flexible sheet material to form a peripheral hem, means for bending said margins up out of the plane of said piece, means for folding back the bent-up margins against the face of the piece, and a rockable lever operatively connected to both said means and rockable in one direction to cause the margins of the work to be bent up and rockable in the other direction to cause the bent-up margins to be folded back.
2. A device for doubling back the margin of a piece of sheet material of predetermined contour to form a hem thereon, comprising a support having a shaped cavity therein to receive a piece of sheet material, pushing means movable to press said piece into said cavity, a plurality of slide

members movable inwardly to engage the margins of said piece, and a reciprocable member movable in one direction to operate said pushing means to move against the work and in the reverse direction to cause said slide members to move inwardly.

3. A device for doubling back the margin of a piece of sheet material of predetermined contour to form a hem thereon, comprising a support having a shaped cavity therein to receive a piece of sheet material, a lever rockably mounted on said support, a pusher mounted on said lever and movable therewith to press the work into said cavity and to withdraw therefrom, a plurality of slide members movable on said support in the plane thereof into said cavity, and means on said lever operating to move said slide members into said cavity as the pusher is withdrawn from the cavity.

4. A device of the class described, comprising a horizontal support with a cavity therein shaped to receive the work, a group of four folder elements surrounding the cavity slideable on said support in a horizontal plane, means for moving one of said elements inward to project into said cavity, and means responsive to inward movement of said one element to cause the other three elements to move inward simultaneously therewith, said last-mentioned means comprising interengaging cam faces on each said element and the elements contiguous thereto.

5. A device of the class described, comprising a horizontal support having a cavity therein shaped to receive the work, a group of four folder elements horizontally slideable on said support to project into said cavity from the sides thereof, means operable to impart inward movement to one of said elements, interengaging cam faces on said one element and the two elements adjacent thereto arranged to cause said adjacent elements to move toward each other in response to inward

movement of said one element, and interengaging cam faces on said adjacent elements and the element opposite to said one element arranged to cause said opposite element to move toward said one element in response to movement of said elements toward each other.

6. In a device for doubling back the margins of a piece of flexible sheet material of which the perimeter has continuous convex curvature to form a peripheral hem, folding means comprising a plurality of pairs of horizontal flat members slideable in a common plane toward one another, each said member presenting an arcuate edge to the opposite member, the end portions of each said edge vertically overlapping end portions of the edges of the members adjacent thereto.

7. A device for doubling back the margins of a piece of flexible sheet material of predetermined contour to form a peripheral hem thereon, comprising a horizontal support having a cavity therein shaped to receive the work, means movable vertically to push the work into said cavity and to indent the work to form lines of fold, and means slideable on said support to double back along said lines the margins of the piece against the face thereof.

8. In a device for doubling back the margins of a piece of flexible sheet material to form a peripheral hem, a horizontal support member having a shaped aperture corresponding to the contour of the finished work piece, a plurality of slides below said support presenting edges in approximate registry with the contour of the aperture, each said edge having a downward facing shoulder, means for pushing a work piece through said aperture to cause the marginal portions to bend up and the edges of the piece to engage said shoulders, and means for advancing said slides inward to fold back said margins.

LIONEL G. VACHON.
